(57) **CLAIM**

The ornamental design for a combined decorative pet leash and collar, as shown and described.

DESCRIPTION

FIG. 1 is a perspective view of a combined decorative pet leash and collar, showing our new design;

FIG. 2 is a right side view thereof;

FIG. 3 is a top plan view thereof;

FIG. 4 is an end view from the handle end thereof; and,

FIG. 5 is an end view from the collar end thereof.

The broken line showing in the views is for illustrative purposes only and forms no part of the claimed design.

The figures have been shown broken away for ease of illustration.
